UNITED STATES PATENT OFFICE.

GUSTAVE F. KOLB, OF MOUNT VERNON, NEW YORK.

BACK FOR BRUSHES OR SIMILAR TOILET ARTICLES.

SPECIFICATION forming part of Letters Patent No. 723,611, dated March 24, 1903.

Application filed March 19, 1902. Serial No. 93,935. (No model.)

To all whom it may concern:

Be it known that I, GUSTAVE F. KOLB, a citizen of the United States, and a resident of Mount Vernon, Westchester county, State of New York, have invented certain new and useful Improvements in Backs for Brushes or Similar Toilet Articles, of which the following is a specification.

This invention relates to a back for brushes, mirrors, and similar toilet articles; and the object is to provide a back that may have different patterns upon sets of goods possessing the same general design, so that different pictures from one and the same artist may be reproduced upon sets of goods which are otherwise similar. To accomplish this, I provide a frame which may have a general design for different sets and a panel which may be ornamented in any way and fitted into the opening in the frame, so that different sets of similar frames or different pieces of a single set may be differently ornamented.

My invention consists in the manner of securing these panels to the frame, and embodies a novel construction and aggroupment of parts, all as will be more fully described in the following description and pointed out in the appended claim.

In the accompanying drawings, Figure 1 is a face view of the frame with the panel omitted; Fig. 2, a side view of the brush complete; Fig. 3, a face view of the panel detached; Fig. 4, a section on line 4-4, Fig. 1, with the panel omitted; Fig. 5, a similar section with the panel in place, and Fig. 6 a detail of the joint between frame and panel.

The back is composed, essentially, of two parts—a frame and a panel. The frame *a*, Figs. 1 and 4, is made of annular form and runs out into the handle *a'*. The annular portion of the frame *a*, inclosing the opening *a*², is provided along its inner edge with a downwardly-projecting flange *a*³, such flange extending at right angles to the general plane of the back.

The panel *b* is of a size and contour to fit against the flange *a*³ of frame *a*. Along its edge it is provided with a shoulder *b'*, that fits against the flange *a*³, and with a laterally-extending flange *b*², extending at right

angles to flange *a*³—viz., parallel to the general plane of the back. When the panel is fitted to its seat, the flange *b*² will extend beyond flange *a*³ and underneath the frame *a*, Fig. 6, so that a groove or channel is formed 55 between the flanges *a*³ *b*². The flange *b*² is shorter than the width of the frame *a*, Fig. 5, so that an opening is formed between the outer edge of the flange *b*² and the inner side of the frame *a*. In this way the groove over the 60 flange *b*² is open laterally and may be filled in with solder *c*, which is introduced around the edge of the flange. The groove when thus filled securely connects the panel *b* to the back *a*, the solder flowing also between 65 the flange *a*³ and the shoulder *b'* to form a tight joint.

The frames *a* are struck up in suitable dies, while the panels *b* may be embossed, enamelled, etched, engraved, or ornamented in 70 other suitable manner.

By my invention I may provide the frames *a* with any one of a number of panels *b*, so that different sets of similar frames or the different pieces of a single set may be differently ornamented. Thus I am enabled to obtain a large assortment in an expensive 75 line of goods without increasing to an appreciable extent the cost of such goods.

The head of the brush *d* when fitted into 80 the frame *a* and secured to the outer edge thereof covers the soldered joint between frame and panel and conceals the connection entirely from view.

What I claim is—

A back for a toilet-brush composed of a frame having an inner flanged edge, a panel having a marginal flange engaging and projecting beyond the flange on the frame to form a laterally-opening groove accessible 90 from the back side of the frame, and cementing material filled in said groove to secure the panel to the frame.

Signed by me at New York city, New York, this 18th day of March, 1902.

GUSTAVE F. KOLB.
